Attn:

UNITED STATES PATENT OFFICE.

CLYDE S. PELTON, OF CLEVELAND HEIGHTS, OHIO.

DESIGN FOR A HEATER FOR SELF-PROPELLED VEHICLES.

49,440.

Specification for Design.

Patented July 25, 1916.

Application filed January 24, 1916. Serial No. 74,053. Term of patent 14 years.

To all whom it may concern:

Be it known that I, CLYDE S. PELTON, a citizen of the United States, and a resident of Cleveland Heights, in the county of Cuyahoga and State of Ohio, have invented a new, original, and ornamental Design for Heaters for Self-Propelled Vehicles, of which the following is a specification, reference being had to the accompanying drawing, forming part hereof, wherein is shown

a perspective view of a heater for self-propelled vehicles, exhibiting my new design.

I claim:—

The ornamental design for a heater for self-propelled vehicles as shown.

CLYDE S. PELTON.
